Primary Examiner — Jae Liang(74) *Attorney, Agent, or Firm* — Barnes & Thornburg LLP(57) **CLAIM**

We claim the ornamental design for a beverage container, as shown and described.

DESCRIPTION

FIG. 1 is a top perspective view of a beverage container according to the new design.

FIG. 2 is a bottom perspective view of the beverage container shown in FIG. 1.

FIG. 3 is a front elevation view of the beverage container shown in FIG. 1.

FIG. 4 is a rear elevation view of the beverage container shown in FIG. 1.

FIG. 5 is a left side elevation view of the beverage container shown in FIG. 1.

FIG. 6 is a right side elevation view of the beverage container shown in FIG. 1.

FIG. 7 is a top plan view of the beverage container shown in FIG. 1; and,

FIG. 8 is a bottom plan view of the beverage container shown in FIG. 1.
